CLASP

John B. Freysinger, New Britain, Conn., assignor to North and Judd Manufacturing Company, New Britain, Conn., a corporation of Connecticut

Application September 2, 1936, Serial No. 99,101

5 Claims. (Cl. 24—73)

This invention relates to an improved type of clasp and has particular application in adjustably and removably securing a flexible curtain across a portion of a travelling case to provide 5 a separate storage compartment therein.

Heretofore, in the packing of delicate wearing apparel which tends to become easily jammed and creased, it has been common practice to carefully fold the apparel and secure it within the 10 cover of a travelling case, such as a suitcase, by means of a flexible curtain secured at one side within the cover and removably secured in stretched position across the apparel by means of a clasp hook engageable with the other side 15 of the cover. It is well-recognized that if curtains of this type are stretched too tightly, the apparel engaged thereby becomes jammed, and it is difficult to engage and disengage the hook. On the other hand, when these curtains are 20 relatively loosely secured in position, they tend to become easily detached and upset the packed articles. Furthermore, previous types of clasps employed for this general purpose have usually proved difficult to operate in a tightly packed 25 travelling case.

It is, therefore, the aim of my invention to provide a clasp which may be easily and removably engaged, will not, of itself, tend to become detached, and which is particularly adaptable to 30 removably and adjustably secure a curtain across a portion of a travelling case to provide a convenient compartment therein.

It is a further object of my invention to provide a two-part interlocking clasp which is simple 35 in construction, easy to operate, and inexpensive to manufacture.

It is a still further object of my invention to provide a two-part clasp, the parts of which normally tend to cam into interlocked engagement. 40

With these and other objects in view, my invention accordingly consists in the features of construction, combination of elements and arrangement of parts which will be exemplified in 45 the construction hereafter set forth and the scope of the application of which will be indicated in the appended claims.

In the drawing, wherein like numerals indicate like parts:

Figure 1 is a perspective view of a travelling case illustrating one application of my invention;

Fig. 2 is a front elevation of my clasp in attached position;

Fig. 3 is an enlarged view in longitudinal section taken along line 3—3 of Fig. 2; and

Figs. 4 and 5 are perspective views of the two parts of the clasp detached from each other.

In accordance with my invention, I have provided a two-part separable clasp having a frame member A pivotally mounted at one end to one wall of the cover C of a travelling case T, and a movable frame member B adapted to interlock with member A. A pair of cooperating lugs on member A tend to maintain it projecting generally at right angles to the wall of the cover and prevent it from folding rearwardly and inwardly against the cover to an inaccessible position. Movable member B adjustably receives a strap or tape extending from one edge of a curtain D secured at its opposite edge to the case and interengages member A in such manner that it tends to fulerum into interlocked position and normally remains in said position.

Referring to the drawing illustrating one embodiment of my invention, member A, which may be integrally formed by casting, forging, or otherwise shaping metal, is provided with spaced side bars 10 and 11 interconnected at their corresponding ends by the respective transversely extending cross bars 12 and 13 and intermediate of their ends by a reinforcing bar 14. Member A is pivotally secured to the inside face C' of cover C and substantially opposite to the hinged portion of the cover by means of a strap loop 15 passing around an intermediate portion of the cross bar 12 and having overlying ends 15' suitably secured to the cover as by rivets 17. Strap 15 may be composed of either metal or fabric, as desired, and, in the present showing, I locate a reinforcing plate 17' between the heads of the rivets and the strap to prevent the rivet heads from cutting into the strap and to reinforce the strap.

Heretofore, when clasp members have been pivotally mounted in a travelling case, they have been free to swing rearwardly and inwardly against a wall of the travelling case during packing and have thus tended to become covered up 45 by the packed articles. To overcome this inherent difficulty of prior constructions, I have provided a pair of lugs 18 respectively extending laterally from the upper ends of the cross bar 12 and substantially at right angles to side bars 50 10 and 11, as best shown in Fig. 4. These lugs engage the wall of the cover, as illustrated in Fig. 3, and serve to normally hold member A in a position substantially at right angles to such wall, where member A may be easily engaged and 55

disengaged by member B as will be later described. It will be noted, however, that member A is free to swing outwardly and forwardly in a counterclockwise direction, with reference to Fig. 3, and to the position A' wherein it will not interfere with the packing of articles in the case.

As illustrated in Figs. 2 and 4, cross bar 13 is generally stepped in form at each end to aid in removably receiving member B. The lower ends of side bars 10 and 11 each terminate in an upwardly projecting, somewhat U-shaped formation having aligned, inwardly projecting short arms 13' and upward extension 13'' in spaced relation to members 10 and 11 and interconnected at their upper ends by a transverse intermediate portion 13a in the form of an elongated lug which preferably extends rearwardly in the same direction as lugs 18 and has a substantially top flat face 13b. In the illustrated form of my invention, it will be appreciated that all portions of member A lie substantially in the same plane, with the exception of the laterally and rearwardly extending portions of lugs 13a and 18 which may be generally parallel and are located on the same side of member A.

Member B, which is arranged to detachably interlock with member A, may be formed in a similar manner to member A as by casting, forging, or other suitable means, and is provided with a pair of opposed side arms 20 and 21 interconnected by transversely extending bars 22, 23, and 24 which may be substantially parallel. A loop portion, generally indicated at 26, and adapted 30 to interlock with the stepped cross bar 13, is provided with a pair of hooked arms 27 and 28 extending upwardly and generally rearwardly from bar 22 adjacent the ends of the bar, and the upper ends of these arms are interconnected by a transverse bar 30, thus forming an aperture 26' adapted to receive intermediate portion 13a of cross bar 13. Arms 26 and 27 are spaced apart 35 so as to be received within the U-shaped portions of member A, as illustrated in Fig. 2.

In interlocking the parts A and B of my clasp, it is simply necessary to insert cross bar 30 of member B between bars 13 and 14 of member A to the position 13c indicated in Fig. 3, and then move member B downwardly so that bar 13 passes through aperture 26', and hook arms 27 and 28 respectively engage against members 13'. It will be noted that at this time the hook arms tend to fulcrum on bars 13', thus locating bar 30 beneath the rearwardly extending portion of lug 13a and against members 13'' (Fig. 3), so that bar 30 is normally urged into a locked position with a camming action, thus preventing any tendency of the clasp to become detached. In the event that the tension of curtain D makes it difficult to stretch members A, D, 15 and 32 to a closed position, bar 30 may be first engaged on face 13b and thereafter slidably moved rearwardly into locked position. As shown in Fig. 3, it will be noted that face 13b may slope slightly in a rearwardly direction to facilitate this interlocking movement. When it is desired to disengage my clasp, it is simply necessary to pivotally swing arms 27 and 28 about their fulcrum supports 13' until aperture 26' is in alignment with bar 13a as indicated by position 13d after which member B may be lifted upwardly and outwardly from engagement with member A.

A suitably shaped downwardly depending tongue 31 is provided intermediate of the ends of bar 24 to form a convenient handle whereby

member B may be easily manipulated into engaged and disengaged position. In the present instance, tongue 31 is bent outwardly to provide a convenient gripping portion, but it will be appreciated that any type of handle may be provided to accomplish this purpose. 5

As is usual in providing a strap adjustment on a buckle or other similar member, the intermediate bar 23 is out of planar relation with bars 22 and 24 so that a flexible strap 32, secured to the end of a curtain by suitable means such as a rivet 33, may pass under bar 24, over bar 23, under bar 22, and thence back in looped overlapping relation above bar 23 and beneath bar 24. When no tension is exerted, the loops of the strap passing above and beneath the respective bars may be slidably positioned to properly locate member B relative to curtain D. However, it will be evident that the friction of the overlapped portions of the strap will tend to normally 20 maintain member B in a preadjusted position.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense. 25

It is also to be understood that the language used in the following claims is intended to cover all of the generic and specific features of the invention herein described and all statements of the scope of the invention which, as a matter of language, might be said to fall therebetween. 30

I claim as my invention:

1. A clasp comprising, in combination, two members adapted to detachably interlock, one of said members having a transversely extending cross bar and spaced side bars, stepped portions respectively connecting the ends of said cross bar to the ends of the side bars, a looped end on the other of said members adapted to fit over and detachably interlock with said cross bar, and means on said cross bar tending to normally maintain said members in interlocked engagement. 45

2. A clasp comprising, in combination, two members, one of said members having a cross bar extending between spaced side bars, stepped portions integral with and respectively connecting an intermediate portion of the cross bar with said side bars, a looped end on the other of said members and having a transversely extending bar, said looped portion being adapted to fit over the intermediate portion of the cross bar, and a laterally projecting lug on said intermediate portion whereby the transverse bar will be engaged beneath said lug and said members will be maintained together in interlocked relation. 55

3. A clasp comprising, in combination, two members, one of said members having a pair of spaced side bars interconnected by spaced transversely extending cross bars, one of said cross bars having an intermediate transverse portion integrally and respectively secured at its opposite ends to the corresponding ends of the side bars by substantially U-shaped portions, a lug laterally extending from the intermediate portion, said other member having a pair of substantially hook shaped side arms interconnected at their respective outer ends by a transverse bar and forming a looped portion adapted to fit over said intermediate portion of the cross bar, the side arms entering into fulcrumed engagement with said U-shaped portions and pivotally urging 70 75

the transverse bar at the end of the loop beneath said lug whereby the two members are in interlocked engagement.

4. A clasp adapted to removably and adjustably secure a curtain across a travelling case and comprising two interengaging detachable members, means pivotally securing one of said members to a wall of the travelling case, means normally tending to maintain said member projecting from said wall of the case, said other member adjustably receiving a strap secured to the curtain, and means detachably securing said members together in such manner that they will not tend to become detached under normal usage.
5. A clasp adapted to removably and adjustably secure a curtain across a travelling case, comprising two detachable interlocking members,

one member having transversely extending cross bars, means pivotally securing one of said cross bars to a wall of the travelling case, a rearwardly extending positioning lug on the pivoted cross bar adapted to engage said wall when said member is substantially at right angles to the wall, a rearwardly extending locking lug on another of the cross bars, said other member having a plurality of spaced bars adapted to adjustably receive a tension strap secured to the curtain, and having a loop adapted to pass over said rearwardly extending locking lug and interlock beneath same, said positioning lugs maintaining said first member and locking lug in a fixed position as said second member is moved into interlocking position.

JOHN B. FREYSINGER.
